DISCHARGE LAMP BALLAST ASSEMBLY

John Shaheen, West Roxbury, Mass., assignor to
Sylvania Electric Products Inc., Salem, Mass.,
a corporation of Massachusetts

Application August 23, 1945, Serial No. 612,274

1 Claim. (Cl. 175—298)

1

This invention relates to an electric discharge lamp ballast assembly and more particularly to a supporting plate for assembling the parts of a ballast and to the mounting thereon of a condenser and a plurality of inductors.

An object of this invention is to provide a mounting for the parts of a ballast, said mounting to save substantial weight.

Another object of this invention is to provide an open type ballast with sufficient ventilation to eliminate external heat.

Another object of this invention is to provide a ballast readily assembled and cheaper to produce commercially than ballasts heretofore assembled.

A feature of this invention is that the ballast may be protected by the usual method of impregnation, said method of sealing and impregnating the ballast depending upon the use of the device and its location with respect to the fixture. The ballast may be sealed as a solid mass and impregnated with a resinous mixture or the parts may be coated individually, assembled, covered with a tarry substance and the entire ballast covered with a metal casing. The latter method provides an explosion-proof device which will stand the test of use outside an appliance in all kinds of atmosphere.

Another feature of this invention is the position of the condenser outside the plurality of inductors, thus producing a device so much cooler than ballasts previously assembled that smaller units may be used. Furthermore, the elimination of considerable heat in the ballast prevents any melting of the potting compound and leakage resulting therefrom.

Other objects, advantages, and features of this invention will be apparent from the detailed description taken in conjunction with the accompanying drawings, in which:

Figure 1 is a perspective view of the assembled ballast before being impregnated and sealed;

Figure 2 is a perspective view of the metal plate on which are mounted the condenser at one end and the transformer and two reactors end to end on the inwardly projecting steps at the other end; and

Figure 3 is a cross-sectional view of the plate showing the trough through which the wires pass to the terminal attachments.

In Figure 1, the condenser 1 is mounted at one end of the supporting plate 2; the transformer 3 and the two reactors 4 are supported end to end on the inwardly projecting steps of the plate, thus allowing the lead wires to pass

2

through the trough to the terminal plate 5. On the terminal plate 5, are mounted the pins 6 for wire attachments. On the supporting plate are placed projecting tabs 7 for fitting over the projecting edges 8 of the condenser 1, thus holding it firmly in place. 9 and 10 represent slots in the supporting plate for attaching the ballast to the fixture.

In Figure 2, the plate 2 is flanged longitudinally for holding the condenser and inductors in place and is further designed with inwardly projecting steps 11 on which the inductors rest. In conjunction with the part of the plate between the inwardly projecting steps 11 the inductors form a duct for the wires to pass to the terminal plate. Furthermore, at the other end of the basic and supporting plate are the tabs 7 for holding the condenser firmly in place. At the ends of the supporting plate are the slots 9 and 10 for attaching the ballast to the fixture.

In Figure 3, the tab 7 for holding the condenser is shown projecting from the plate. By resting on the inwardly projecting steps 11, the inductors form a duct 12 for wires. The flanges 13 extend throughout the length of the plate.

What I claim is:

A ballast assembly for electric discharge lamps, said ballast assembly comprising: a unitary elongated metal supporting piece having its bottom portion substantially flat and having upwardly-extending longitudinal flange portions along substantially its entire length and having along part only of its length a pair of re-entrant steps, each step extending upwardly from said bottom portion and inwardly from a flange portion, a plurality of inductors placed end to end and mounted between said flanges and resting on said steps to form a duct, and a condenser extending between the flanges and fixed to the bottom of said metal piece at the end of said pair of reentrant steps at the end of the duct.

JOHN SHAHEEN.
